UNITED STATES PATENT OFFICE.

ASA LENDO STUTTS, OF UNION, SOUTH CAROLINA, ASSIGNOR TO MONARCH BOBBIN CLEANER CO., OF UNION, SOUTH CAROLINA, A CORPORATION OF SOUTH CAROLINA.

BOBBIN-CLEANING MACHINE.

1,412,719. .

Specification of Letters Patent. Patented Apr. 11, 1922.

Application filed November 3, 1920. Serial No. 421,505.

To all whom it may concern:

Be it known that I, ASA LENDO STUTTS, a citizen of the United States, residing at Union, in the county of Union and State of South Carolina, have invented certain new and useful Improvements in Bobbin-Cleaning Machines; and I do hereby declare the following to be a full, clear, and exact description of the invention, such as will enable others skilled in the art to which it appertains to make and use the same.

My invention relates to improvements in bobbin cleaners, and is intended to provide a machine from which the rovings from partly unwound bobbins may be quickly and effectively removed without the necessity for any special manipulation, or any special attention on the part of the operator during the cleaning process; and in which the bobbins to be cleaned may be fed indiscriminately into a hopper and the clean bobbins may be removed from the other end of the machine, while the rovings are removed from the bobbins as they pass through the machine without material injury to the fibre, and said rovings are caught by a suction blast and carried to a condenser from whence they are delivered to any suitable receptacle.

My invention will be more fully understood after reference to the accompanying drawings, in which like parts are indicated by similar reference symbols throughout the several views, and in which:—

Figure 1 is a side elevation of the complete machine.

Figure 2 is a plan view of the complete machine.

Figure 3 is an end view of the complete machine as seen from the right of Figure 2.

Figure 4 shows a vertical section along the broken line 4—4 of Figure 2, and looking in the direction of the arrows.

Figure 5 is a fragmentary view showing one of the link belts with the bobbin holders mounted thereon, the parts being shown on a larger scale than in the former figures.

Figure 6 shows a section along the line 6—6 of Figure 5, parts being shown in plan.

Figure 7 shows a section along the line 7—7 of Figure 6, and looking in the direction of the arrows.

Figure 8 shows a section along the line 8—8 of Figure 6, and looking in the direction of the arrows.

Figure 9 is a plan view of the metal plat-

form or shelf on which the bobbins are fed from the hopper, and illustrates the yielding springs for arresting the movement of the bobbins until caught by the bobbin holders.

Figure 10 is an end view of the parts shown in Figure 9, as seen from the left of said figure.

Figure 11 shows a section along the line 11—12 of Figure 9, and shows a section 65 through the bobbin as it first engages the yielding spring arm; and

Figure 12 is a similar view to Fig. 11, except it shows the bobbin just as it is being released by the yielding spring arm. 70

A and A' are two cross beams or plates secured to any suitable bed plate or platform A° in any convenient way, as by means of the screw bolts a.

Secured to the plates A and A' are the 75 side frames B, and the vertical stanchions B' and B'', flanged as at b and secured to the plates A and A' by means of suitable bolts b'. These side frames also comprise longitudinal beams B³ and B⁴, which serve as supports for the various shafts hereinafter mentioned. 80

Mounted between the opposite side frames, and secured respectively thereto, is the hopper C, in which the bobbins to be cleaned are 85 thrown, which hopper is provided with a reduced throat C'.

To each of the side frames B a double track is connected, the outer member D of which is connected to the frame B by the 90 braces d, see Figure 3, and this outer member of the double track is of continuous elliptical form provided with a continuous slot d⁰, see Figs. 2 and 5—7. Parallel to the outer track of each set of tracks is the inner track 95 D', which is secured directly to the frame B and is provided with a similar groove d⁰ oppositely disposed to the corresponding groove in the outer track, as shown in Figure 4. This inner track is also substantially 100 elliptical, and has a continuous bottom and ends, but the upper portion of the track is broken away throughout a part of its length, as indicated in Figs. 2, 4 and 6. The inner track D' is curved inwards at the two ends 105 of the break, as shown at d' (see Figs. 6 and 2) for reasons that will be later described.

Mounted between the side frames B is the hopper E, which is open at the top to receive the rovings stripped off of the bobbins, which 110

hopper is connected by the air trunk E' to the suction chamber E², in which is mounted a suction fan M⁰, and this chamber E² is connected by the trunk F' to the top of the condenser G which is preferably covered by the woven wire top g', which is shown as broken away in Figure 2.

In the bottom of this condenser G are the condenser rollers G' which are driven, as 10 will be hereinafter described.

Mounted in rear of the hopper E is a chute H, see Figs. 1, 2 and 4, to receive the cleaned bobbins, which conveys said bobbins to any suitable receptacle which may be placed beneath the mouth h of said chute, see Figs. 1 and 4. Extending across the frame B, near its front end, is a horizontal shelf or apron I, shown in Fig. 4, and in detail in Figs. 9 to 12. This shelf I is preferably a metal plate 15 provided with downwardly projecting flanges I', secured by the bolts i to the frame B. This shelf is slotted on opposite sides, as at I^o, to permit the movement upwards of the stop rollers J, carried by the yokes J', which 20 are connected to the leaf springs J² held in the clamps J³, shown in detail in Figures 9 to 12. The function of these springs and rollers 25 will be hereinafter described.

The foregoing description relates more 30 especially to the fixed parts of the apparatus, but without describing the details of the moving parts, and these will now be described.

K represents the main driving shaft which 35 is driven from any suitable source of power, and is provided with several pulleys engaging corresponding belts. The pulley K', mounted on this shaft K, drives the belt L which drives the smaller pulley M on the 40 shaft M', and this drives the fan M⁰ at a high speed. The pulley K² on the shaft K drives the belt L², which belt engages the smaller pulleys N, N' and N² on the shafts n, n' and n² carrying the brushes O, O' and O², as 45 shown most clearly in Figure 4.

The pulleys N, N' and N² are so dimensioned with regard to the pulley K² that if the shaft K is rotating at 300 revolutions per minute, the brush O will rotate at a greater 50 velocity, say 800 revolutions per minute, and the brushes O' and O² at still increasing velocity, or say 850 and 900 revolutions per minute, respectively. The brushes O and O' may be moved forwards or away from the 55 bobbin carriers by adjusting screws and nuts O³, and these brushes are preferably arranged so that the brush O cleans the bobbins and the brushes O' and O² serve as cleaning brushes to remove the rovings, respectively, 60 from the brush O and the brush O'.

The small pulley K³ on the driving shaft K engages the belt L³ which drives the larger pulley P at a reduced speed, say 50 revolutions per minute, and this pulley P is mounted 65 on a shaft P' carrying the pulley P², see

Fig. 4, which drives the belt L⁴ engaging the larger pulley Q on the shaft Q' at a further reduced speed, say 8½ revolutions per minute. This shaft Q' carries a pair of sprocket wheels Q² which engage the sprocket chains R, which chains pass over corresponding sprocket wheels Q³ at the opposite end of the machine, mounted on the shaft Q⁴. 70

These shafts Q' and Q⁴ are journaled in yokes S which may be adjusted relative to the frame F by means of the adjusting screws s, see Figure 4. The shaft Q' also carries a pulley Q⁰, see Figure 1, which drives the belt L⁵, which belt L⁵ drives a pulley G² on the shaft of one of the condenser rolls G'. These 80 condenser rolls are connected together by the gears g, so that as the main shaft continues to revolve these condenser rolls draw the rovings down and squeeze the air out and deliver them to any suitable receptacle, not shown. 85

The chains R carry the extensible bobbin holders at opposite sides of the track, as will now be described.

The bobbins are of the usual shape and perforated throughout, as shown at Z in Figure 4, and each perforated end of the bobbin is adapted to be engaged by the spring impressed tip of the bobbin holder, preferably in the shape of a cylinder with a tapered point, shown in Figures 2 and 3, and on a 90 larger scale in Figures 5 and 6. Each bobbin holder T is provided with a cylindrical shell t having an outwardly projecting lug t' engaging in the groove d^o in the outer track D, as shown most clearly in Figure 8. This cylindrical shell is provided with a downwardly projecting lug t^o adapted to engage one of the links of the chain R by which the shell is caused to move transversely to its axis. 100

Slidably mounted in the shell is the plunger T' which is normally pressed outwards by the spring T², and has a stop rib t² adapted to engage the washer t³ which is secured on the interior of the hollow shell t. This plunger T' is provided with a blunt 110 pointed tip t⁴ which is adapted to be pressed into the perforations in the end of the bobbin under the action of the spring T², as will be hereinafter described.

Each plunger T' has an upwardly projecting lug t⁵ which is adapted to engage a cam u on the cam plate U, see Figs. 1 and 2, when it is desired to withdraw the point of the plunger from engagement with the end of the bobbin, and consequently to 120 release the bobbin and to permit it to fall away from the bobbin holder.

Having thus described the construction of the various parts in detail, the operation of the complete apparatus will now be described. 125

It is, of course, assumed that the main shaft is rotating, and that the various parts are in motion. The bobbins to be cleaned with the rovings on are thrown indiscrimi- 130

nately in the hopper C and tend to roll down towards the throat C' as shown in Figure 4. As each bobbin reaches the shelf I its ends bring up against the spring impressed 5 rollers J, tending to prevent the bobbin from rolling forwards on the shelf, as shown in Figs. 4 and 11. At the moment when these rollers J are pressed down, as shown in Figure 12, the pointed ends t⁴ of the respective 10 bobbin holders will pass clear of the curved ends d' of the two inside tracks D', and the points of these spring plungers T' will snap into engagement with the ends of the axial opening through the bobbin, thus 15 serving as journal bearings for the bobbins.

As the bobbins are carried forward in the direction of the arrow in Figure 4 they will be presented seriatim to the cleaning 20 brush O, and the rovings will be torn off without unnecessarily breaking or injuring the fibre, and the teeth of this brush O will be cleaned by the doffing or cleaning brushes O' and O². The rovings torn loose from 25 the cleaned bobbins are sucked down through the hopper E and air trunk E' to the suction fan and are forced by the blast up through the trunk F to the condenser G, where the excess air escapes through the 30 screen at the top of the said chamber, and the rovings falling down into the bottom of said chamber are caught between the rolls G' and are delivered in the form of a bat to any suitable receptacle, not shown.

35 After the rovings have been cleaned off of the bobbins, the bobbins are fed still further forward until the lugs t⁵ on the plungers T' engage the cam faces u and retract the points t⁴ of said plungers from engagement 40 with the ends of the bobbins, and then the released bobbins fall down into the inclined chute H, and, passing through the mouth h of said chute, may be collected in any suitable receptacle, not shown.

45 It will be noted that the only manual work incident to the operation of the machine is the throwing of the bobbins into the hoppers C and removing the condensed roving from the bottom of the condenser G 50 and removing the cleaned bobbins after they fall from the chute H.

None of these hand operations requires any skilled labor at all, and there is no necessity for an attendant to touch the bobbin from the time it is thrown into the hopper C until the cleaned bobbin comes out of the machine, or for him to touch the roving in any way until it is carried from the hopper C through the apparatus 60 and falls out of the bottom of the condenser G.

While I have shown the brush O only used for cleaning off the bobbins, it will be obvious that the brush O' may also be 65 caused to directly engage with the bobbin

if desired, leaving only a single doffing brush O².

So that the frame B may be kept taut at all times, and that the operation of the bobbin holders may be properly timed for gripping 70 and releasing, I provide the adjusting mechanism for the shaft comprising the yokes S and the other parts for regulating the same shown in Figs. 1 and 4. Any other suitable adjusting means may be provided for 75 other parts of the apparatus as may be desired.

It will be obvious also that various modifications in the herein described construction, and in the combination and arrangement of parts might be made which could be used without departing from the spirit of my invention; and I do not mean to limit the invention to such details except as particularly pointed out in the claims. 80 85

I claim:

1. Apparatus for removing the rovings from bobbins, comprising a feed hopper, tracks located below said hopper, endless chains moving between said tracks, bobbin 90 holders carried by said endless chains and engaging said tracks, means for causing said bobbin holders to operate in pairs and to grip the ends of said bobbins, means for stripping the rovings from said bobbins 95 while held in said bobbin holders, means for releasing the cleaned bobbins from said holders, and means for carrying away the rovings after removal from said bobbins.

2. Apparatus for removing the rovings 100 from bobbins, comprising a feed hopper, a receiving shelf mounted below said hopper, tracks also located below said hopper, endless chains moving between said tracks, bobbin 105 holders carried by said endless chains and engaging said tracks, means coacting with said shelf to present the ends of the bobbins to said bobbin holders, means for causing said bobbin holders to operate in pairs and to grip the ends of said bobbins, 110 means for stripping the rovings from said bobbins while held in said bobbin holders, means for releasing the cleaned bobbins from said holders, and means for carrying away the rovings after removal from said bobbins. 115

3. Apparatus for removing the rovings from bobbins, comprising a feed hopper, tracks located below said hopper, endless chains moving between said tracks, bobbin 120 holders carried by said endless chains and engaging said tracks, means for causing said bobbin holders to operate in pairs and to grip the ends of said bobbins, a rotary brush for stripping the rovings from said bobbins while held in said bobbin holders, means for cleaning said brush, means for releasing the cleaned bobbins from said holders, and means for carrying away the rovings after removal from said bobbins. 125

4. Apparatus for removing the rovings 130

from bobbins, comprising a feed hopper, a receiving shelf mounted below said hopper, tracks also located below said hopper, endless chains moving between said tracks, bobbin 5 holders carried by said endless chains and engaging said tracks, means coacting with said shelf to present the ends of the bobbins to said bobbin holders, means for causing said bobbin holders to operate in pairs and to grip 10 the ends of said bobbins, a rotary brush for stripping the rovings from said bobbins while held in said bobbin holders, means for cleaning said brush, means for releasing the cleaned bobbins from said holders, and 15 means for carrying away the rovings after removal from said bobbins.

5. Apparatus for removing the rovings from bobbins, comprising a feed hopper, tracks located below said hopper, endless 20 chains moving between said tracks, bobbin holders carried by said endless chains and engaging said tracks, means for causing said bobbin holders to operate in pairs and to grip the ends of said bobbins, means for 25 stripping the rovings from said bobbins while held in said bobbin holders, means for releasing the cleaned bobbins from said holders, a hopper for the removed rovings mounted beneath said stripping means, a suction 30 fan, a condenser, and air trunks connecting said last mentioned hopper with said fan, and said fan with said condenser.

6. Apparatus for removing the rovings from bobbins, comprising a feed hopper, a 35 receiving shelf mounted below said hopper, tracks also located below said hopper, endless chains moving between said tracks, bobbin holders carried by said endless chains and engaging said tracks, means coacting 40 with said shelf to present the ends of the bobbins to said bobbin holders, means for causing said bobbin holders to operate in pairs and to grip the ends of said bobbins, means for stripping the rovings from said 45 bobbins while held in said bobbin holders, means for releasing the cleaned bobbins from said holders, a hopper for the removed rovings mounted beneath said stripping means, a suction fan, a condenser, and air trunks 50 connecting said last mentioned hopper with said fan, and said fan with said condenser.

7. Apparatus for removing the rovings from bobbins, comprising a feed hopper, tracks located below said hopper, endless 55 chains moving between said tracks, bobbin holders, each provided with a spring impressed plunger, said holders being attached to and carried by said endless chains and engaging said tracks, means for causing said 60 plungers to operate in pairs and to engage the ends of said bobbins, means for stripping the rovings from said bobbins while held in said bobbin holders, means for withdrawing said plungers and thereby releasing the 65 cleaned bobbins from said holders, and

means for carrying away the rovings after removal from said bobbins.

8. Apparatus for removing the rovings from bobbins, comprising a feed hopper, a receiving shelf mounted below said hopper, tracks also located below said hopper, endless chains moving between said tracks, bobbin 70 holders, each provided with a spring impressed plunger, said holders being attached to and carried by said endless chains and 75 engaging said tracks, means coacting with said shelf to present the ends of the bobbins to said bobbin holders, means for causing said plungers to operate in pairs and to engage the ends of said bobbins, means for stripping the rovings from said bobbins 80 while held in said bobbin holders, means for withdrawing said plungers and thereby releasing the cleaned bobbins from said holders, and means for carrying away the rovings 85 after removal from said bobbins.

9. Apparatus for removing the rovings from bobbins, comprising a shelf, means for feeding said bobbins to said shelf, a pair of tracks located at each side of said shelf, endless chains moving between said tracks, bobbin 90 holders, each provided with a spring impressed plunger, said holders being attached to and carried by said endless chains and 95 engaging said tracks, means for causing said plungers to operate in pairs and to engage the ends of said bobbins while on said shelf, means for stripping the rovings from said bobbins while held in said bobbin holders, and means for withdrawing said plungers 100 and thereby releasing the cleaned bobbins from said holders.

10. Apparatus for removing the rovings from bobbins, comprising a shelf, means for feeding said bobbins to said shelf, a pair of 105 tracks located at each side of said shelf, endless chains moving between said tracks, bobbin holders, each provided with a spring impressed plunger, said holders being attached to and carried by said endless chains and 110 engaging said tracks, means co-acting with said shelf to present the ends of the bobbins to said bobbin holders, means for causing said plungers to operate in pairs and to engage the ends of said bobbins, means for stripping the rovings from said bobbins while held in 115 said bobbin holders, and means for withdrawing said plungers and thereby releasing the cleaned bobbins from said holders.

11. Apparatus for removing the rovings from bobbins, comprising a shelf, means for feeding said bobbins to said shelf, a pair of tracks located at each side of said shelf, yielding spring impressed guide rollers for guiding the ends of the bobbin carried by 120 said shelf, endless chains moving between said tracks, bobbin holders, each provided with a spring impressed plunger, said holders being attached to and carried by said 125 endless chains and engaging said tracks, 130

means for causing said plungers to operate in pairs and to engage the ends of said bobbins, while on said shelf, means for stripping the rovings from said bobbins while held in said bobbin holders, and means for withdrawing said plungers and thereby releasing the cleaned bobbins from said holders.

12. Apparatus for removing the rovings from bobbins, comprising a shelf, means for feeding said bobbins to said shelf, a pair of tracks located at each side of said shelf, yielding spring impressed guide rollers for guiding the ends of the bobbin carried by said shelf, endless chains moving between said tracks, bobbin holders, each provided with a spring impressed plunger, said holders being attached to and carried by said endless chains and engaging said tracks, means for causing said plungers to operate in pairs and to engage the ends of said bobbins, means for stripping the rovings from said bobbins while held in said bobbin holders, and means for withdrawing said plungers and thereby releasing the cleaned bobbins from said holders.

13. Apparatus for removing the rovings from bobbins, comprising a frame, a pair of tracks on each side of said frame, endless chains moving between said tracks, bobbin holders carried by said endless chains and engaging said tracks, means for feeding the bobbins to said bobbin holders, means for causing said bobbin holders to operate in pairs and to grip the ends of said bobbins, means for stripping the rovings from said bobbins while held in said bobbin holders, means for releasing the cleaned bobbins from said holders, a hopper for the removed rovings mounted beneath said stripping means, a suction fan, a condenser, and air trunks connecting said last mentioned hopper with said fan, and said fan with said condenser.

14. Apparatus for removing the rovings from bobbins, comprising a frame, a pair of tracks on each side of said frame, a receiving shelf for the bobbins, endless chains moving between said tracks, bobbin holders carried by said endless chains and engaging said tracks, means coacting with said shelf to present the ends of the bobbins to said bobbin holders, means for causing said bobbin holders to operate in pairs and to grip the ends of said bobbins, means for stripping the rovings from said bobbins while held in said bobbin holders, means for releasing the cleaned bobbins from said holders, a hopper for the removed rovings mounted beneath said stripping means, a suction fan, a condenser, and air trunks connecting said last mentioned hopper with said fan, and said fan with said condenser.

15. Apparatus for removing the rovings from bobbins, comprising a frame, a pair of

tracks on each side of said frame, endless chains moving between said tracks, bobbin holders carried by said endless chains and engaging said tracks, means for feeding the bobbins to said bobbin holders, means for causing said bobbin holders to operate in pairs and to grip the ends of said bobbins, a rotary brush for stripping the rovings from said bobbins while held in said bobbin holders, means for cleaning said brush, means for releasing the cleaned bobbins from said holders, and means for carrying away the rovings after removal from said bobbins.

16. Apparatus for removing the rovings from bobbins, comprising a frame, a pair of tracks on each side of said frame, a receiving shelf for the bobbins, endless chains moving between said tracks, bobbin holders carried by said endless chains and engaging said tracks, means coacting with said shelf to present the ends of the bobbins to said bobbin holders, means for causing said bobbin holders to operate in pairs and to grip the ends of said bobbins, a rotary brush for stripping the rovings from said bobbins while held in said bobbin holders, means for cleaning said brush, means for releasing the cleaned bobbins from said holders, and means for carrying away the rovings after removal from said bobbins.

17. Apparatus for removing the rovings from bobbins, comprising a frame, a pair of tracks on each side of said frame, endless chains moving between said tracks, bobbin holders carried by said endless chains and engaging said tracks, means for feeding the bobbins to said bobbin holders, means for causing said bobbin holders to operate in pairs and to grip the ends of said bobbins, means for stripping the rovings from said bobbins while held in said bobbin holders, and means for releasing the cleaned bobbins from said holders.

18. Apparatus for removing the rovings from bobbins, comprising a frame, a pair of tracks on each side of said frame, a receiving shelf for the bobbins, endless chains moving between said tracks, bobbin holders carried by said endless chains and engaging said tracks, means coacting with said shelf to present the ends of the bobbins to said bobbin holders, means for causing said bobbin holders to operate in pairs and to grip the ends of said bobbins, means for stripping the rovings from said bobbins while held in said bobbin holders, and means for releasing the cleaned bobbins from said holders.

19. Apparatus for removing the rovings from bobbins, comprising a frame, a pair of tracks on each side of said frame, endless chains moving between said tracks, bobbin holders carried by said endless chains and engaging said tracks, means for feeding the bobbins to said bobbin holders, means for causing said bobbin holders to operate in pairs and to grip the ends of said bobbins, a rotary brush for stripping the rovings from said bobbins while held in said bobbin holders, means for cleaning said brush, means for releasing the cleaned bobbins from said holders, and means for carrying away the rovings after removal from said bobbins.

pairs and to grip the ends of said bobbins, a rotary brush for stripping the rovings from said bobbins while held in said bobbin holders, means for cleaning said brush, and 5 means for releasing the cleaned bobbins from said holders.

20. Apparatus for removing the rovings from bobbins, comprising a frame, a pair of tracks on each side of said frame, a receiving 10 shelf for the bobbins, endless chains moving between said tracks, bobbin holders carried by said endless chains and engaging said tracks, means coacting with said shelf to present the ends of the bobbins to said bobbin holders, means for causing said bobbin 15 holders to operate in pairs and to grip the ends of said bobbins, a rotary brush for stripping the rovings from said bobbins while held in said bobbin holders, means for 20 cleaning said brush, and means for releasing the cleaned bobbins from said holders.

21. Apparatus for removing the rovings from bobbins, comprising a shelf, means for feeding said bobbins to said shelf, a pair of 25 tracks located at each side of said shelf, endless chains moving between said tracks, bobbin holders, each provided with a spring impressed plunger, said holders being attached to and carried by said endless chains and 30 engaging said tracks, means for simultaneously releasing opposite pairs of plungers, thereby causing said plungers to operate in pairs and to engage the ends of said bobbins while on said shelf, means for stripping the 35 rovings from said bobbins while held in said bobbin holders, and a pair of cams engaging said plungers for withdrawing said plungers in pairs and thereby releasing the cleaned bobbins from said holders.

40. 22. Apparatus for removing the rovings from bobbins, comprising a shelf, means for feeding said bobbins to said shelf, a pair of tracks located at each side of said shelf, endless chains moving between said tracks, bobbin 45 holders, each provided with a spring impressed plunger, said holders being attached to and carried by said endless chains and engaging said tracks, means coacting with said shelf to present the ends of the bobbins to said bobbin holders, means for simultaneously releasing opposite pairs of plungers, thereby causing said plungers to operate in pairs and to engage the ends of said bobbins while on said shelf, means for stripping the rovings from said bobbins while held in said bobbin 50 holders, a pair of cams engaging said plungers for withdrawing said plungers in pairs and thereby releasing the cleaned bobbins from said holders.

55. 23. Apparatus for removing the rovings from bobbins, comprising a shelf, means for feeding said bobbins to said shelf, a pair of tracks located at each side of said shelf, yielding spring impressed guide rollers for 60 guiding the ends of the bobbin carried by

said shelf, endless chains moving between said tracks, bobbin holders, each provided with a spring impressed plunger, said holders being attached to and carried by said endless chains and engaging said tracks, 70 means for simultaneously releasing opposite pairs of plungers, thereby causing said plungers to operate in pairs and to engage the ends of said bobbins, while on said shelf, means for stripping the rovings from said bobbins while held in said bobbin holders, and a pair of cams engaging said plungers for withdrawing said plungers in pairs and thereby releasing the cleaned bobbins from 75 said holders.

24. Apparatus for removing the rovings from bobbins, comprising a shelf, means for feeding said bobbins to said shelf, a pair of tracks located at each side of said shelf, yielding spring impressed guide rollers for 80 guiding the ends of the bobbins carried by said shelf, endless chains moving between said tracks, bobbin holders, each provided with a spring impressed plunger, said holders being attached to and carried by said 85 endless chains and engaging said tracks, means for simultaneously releasing opposite pairs of plungers, thereby causing said plungers to operate in pairs and to engage the ends of said bobbins, means for stripping 90 the rovings from said bobbins while held in said bobbin holders, and a pair of cams engaging said plungers for withdrawing said plungers in pairs and thereby releasing the 95 cleaned bobbins from said holders.

25. Apparatus for removing the rovings from bobbins, comprising a shelf, means for feeding said bobbins to said shelf, a pair of tracks located at each side of said shelf, endless chains moving between said tracks, bobbin 100 holders, each provided with a spring impressed plunger, said holders being attached to and carried by said endless chains and engaging said tracks, means for simultaneously releasing opposite pairs of plungers, thereby causing said plungers to operate in pairs and to engage the ends of said bobbins while on said shelf, means for stripping the rovings from said bobbins while held in said bobbin 105 holders, a pair of cams engaging said plungers for withdrawing said plungers in pairs and thereby releasing the cleaned bobbins from said holders, a hopper for the removed rovings mounted beneath said stripping means, a suction fan, 110 a condenser, and air trunks connecting said last mentioned hopper with said fan, and said fan with said condenser.

26. In a bobbin stripping machine, an endless carding surface, means for causing the carding surface to travel, and means for causing a bobbin to travel transversely of its axis past and in contact with said carding surface.
